Primary Examiner — Steven J Czyz(74) *Attorney, Agent, or Firm* — Tommy S F Wang;
Wang IP Law Group, P.C.(57) **CLAIM**

The ornamental design for a vial holder, as shown and described.

DESCRIPTION

FIG. 1 is a front perspective view of a vial holder showing my new design;

FIG. 2 is a rear perspective view thereof;

FIG. 3 is a bottom perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof; and,

FIG. 10 is a perspective view of the vial holder shown with environment attached.

The broken lines depict portions of the article and environment that form no part of the claimed design. The dot-dash broken lines in FIGS. 1-7 and 10 represent unclaimed boundary lines and form no part of the claimed design.

1 Claim, 9 Drawing Sheets(56)
